His Attorney

UNITED STATES PATENT OFFICE.

BURKE BRADBURY, OF SCHENECTADY, NEW YORK, ASSIGNOR TO GENERAL ELECTRIC COMPANY, A CORPORATION OF NEW YORK.

SIGNAL-RECEIVING SYSTEM.

Application filed March 28, 1921. Serial No. 454,828.

To all whom it may concern:

Be it known that I, BURKE BRADBURY, a citizen of the United States, residing at Schenectady, in the county of Schenectady, 5 State of New York, have invented certain new and useful Improvements in Signal-Receiving Systems, of which the following is a specification.

My present invention relates to signal receiving systems, and more particularly to 10 signaling systems employing continuous radio frequency currents. The object of my invention is to provide a simple and efficient means for producing an audible indication of signals transmitted by means of radio frequency continuous currents.

In carrying out my invention, I provide 15 at a receiving station a source of audio frequency current which is associated with an electron discharge device and a detector in such a way that when no signaling currents are impressed upon the system there will be no appreciable flow of audio frequency current in the detector circuit. When, however, 20 a radio frequency signaling current is impressed upon the system this signaling current is modulated by means of the audio frequency source and the modulated radio frequency signaling current is trans- 25 mitted to the detector circuit where it is rectified and the rectified current is used to produce the desired audible indication.

The novel features which I believe to be 30 characteristic of my invention are set forth with particularly in the appended claims. My invention itself, however, both as to its organization and method of operation will best be understood by reference to the following description taken in connection with 35 the accompanying drawing in which I have illustrated diagrammatically one way in which my invention may be carried into effect.

As indicated in the drawing, my receiving 40 apparatus comprises an electron discharge device 1 having an electron emitting cathode 2, an anode 3, a third electrode 4 in the form of a plate, and a discharge controlling member or grid 5 interposed between the cathode 45 and other electrodes. By means of the battery 6, a constant positive potential is impressed upon the anode 3 and the third electrode 4 is connected to a point 7 in this

battery so that a smaller positive potential is impressed upon the third electrode 4. The 55 potentials of the battery 6 and the point 7 are preferably so chosen that a negative resistance will be produced in the circuit between cathode and third electrode 4. A source of audio frequency current 8 which is connected in the circuit between the cathode and discharge controlling member impresses upon that circuit at all times an 60 audio frequency current. The circuit between cathode and third electrode contains 65 an inductance 9 and a variable capacity 10 which are tuned to the frequency of the signals which it is desired to receive. An auxiliary circuit containing a detector 11 is coupled by means of the inductance 12 to 70 inductance 9 and this circuit may also be tuned by means of a variable capacity 13 to the frequency of the signals to be received. A resistance 14 is preferably included in the 75 circuit between cathode and third electrode and this resistance is adjusted to a value slightly greater than the critical value at which the circuit becomes self-oscillating so that when no signaling currents are being received no current of signaling frequency 80 will be produced in the circuit.

When no signals are being received no appreciable amount of audio frequency current will be produced in the detector circuit and in the telephone receivers 15 because of the fact that the detector circuit and the circuit with which it is associated are both tuned to the radio frequency of the signal and the coupling between 9 and 12 is too loose to permit the transfer of any appreciable amount of audio frequency current. When signals are received upon the antenna 16 and impressed upon the circuit between cathode and discharge controlling grid by means of the coupling transformer 95 17, the potential of the grid 5 will vary at a radio frequency corresponding to the frequency of the signaling current, this radio frequency being modulated in accordance with the audio frequency source 8. A modulated current of radio signaling frequency 100 will then be produced in the circuit 9, 10 and this modulated radio frequency current will be transferred to the detector circuit by means of the coupling 9, 12, and when rectified in that circuit by the action of the 105

detector 11, will produce an audio frequency current in the telephone receivers 15.

While I have shown and described the preferred embodiment of my invention, it 5 will be apparent that my invention is by no means limited to the particular circuit arrangement shown but that many variations in the connections employed as well as in the form of apparatus used may be made 10 without departing from the scope of my invention as set forth in the appended claims.

What I claim as new and desire to secure by Letters Patent of the United States, is:—

1. The combination in a signal receiving 15 system of an electron discharge device having an electron emitting cathode, an anode, a third electrode and a discharge controlling member, electric circuits connecting said cathode with each of the other electrodes, 20 sources of potential applied to said circuits in such a way as to produce a negative resistance in the circuit between cathode and third electrode, means for impressing signaling currents of radio frequency upon the 25 circuit between cathode and discharge controlling member, means for continuously impressing audio frequency currents upon said circuit and a detector circuit loosely coupled to the circuit between cathode and 30 third electrode, the circuit between cathode and third electrode and the detector circuit being resonant to the signaling frequency and the positive resistance of the circuit between cathode and third electrode being of 35 a value greater than the critical value at which oscillations will be generated in the circuit.

2. The combination in a signal receiving 40 system of an electron discharge device having an electron emitting cathode, an anode, a third electrode and a discharge controlling member, electric circuits connecting said cathode with each of the other electrodes, sources of potential applied to said circuits 45 in such a way as to produce a negative resistance in the circuit between cathode and third electrode, means for impressing signaling currents of radio frequency upon the circuit between cathode and discharge controlling member, means for continuously 50 impressing audio frequency currents upon said circuit and a detector circuit loosely coupled to the circuit between cathode and third electrode, the circuit between cathode and third electrode and the detector circuit being resonant to the signaling frequency.

3. The combination in a signal receiving 55 system of an electron discharge device having an electron emitting cathode, an anode, a third electrode and a discharge controlling member, electric circuits connecting said cathode with each of the other electrodes, sources of potential applied to said circuits 60 in such a way as to produce a negative resistance in the circuit between cathode and

third electrode, means for impressing signaling currents of radio frequency upon the circuit between cathode and discharge controlling member, means for modulating the signaling current at an audio frequency, and 70 a detector circuit loosely coupled to the circuit between cathode and third electrode, the circuit between cathode and third electrode and the detector circuit being resonant to the signaling frequency. 75

4. The combination in a signal receiving system of an electron discharge device having an electron emitting cathode, an anode, a third electrode and a discharge controlling member, electric circuits connecting said cathode with each of the other electrodes, sources of potential applied to said circuits in such a way as to produce a negative resistance in the circuit between cathode and third electrode, means for impressing signaling currents of radio frequency upon the circuit between cathode and discharge controlling member, and a detector circuit loosely coupled to the circuit between cathode and third electrode, the circuit between cathode and third electrode being resonant to the signaling frequency. 80 85

5. The combination in a signal receiving system of an electron discharge device having an electron emitting cathode, an anode, a third electrode and a discharge controlling member, electric circuits, connecting said cathode with each of the other electrodes, sources of potential applied to said circuits in such a way as to produce a negative resistance in the circuit between cathode and third electrode, means for impressing signaling currents of radio frequency upon the circuit between cathode and discharge controlling member, means for modulating the signaling current at an audio frequency, and a detector circuit loosely coupled to the circuit between cathode and third electrode, the circuit between cathode and third electrode being resonant to the signaling frequency. 90 95 100

6. The combination in a signal receiving system of an electron discharge device having an electron emitting cathode, an anode, a third electrode and a discharge controlling member, electric circuits connecting said cathode with each of the other electrodes, sources of potential applied to said circuits in such a way as to produce a negative resistance in the circuit between cathode and third electrode, means for impressing signaling currents of radio frequency upon the circuit between cathode and discharge controlling member, means for continuously impressing audio frequency currents upon said circuit, and a detector circuit loosely coupled to the circuit between cathode and third electrode, the circuit between cathode and third electrode being resonant to the signaling frequency, and the resistance of the circuit 110 115 120 125 130

cuit between cathode and third electrode being of a value greater than the critical value at which oscillations will be generated in the circuit.

- 5 7. The combination in a signal receiving system of an electron discharge device having an electron emitting cathode, an anode, a third electrode and a discharge controlling member, electric circuits connecting said 40 cathode with each of the other electrodes, sources of potential applied to said circuits in such a way as to produce a negative resistance in the circuit between cathode and third electrode, means for impressing signaling currents of radio frequency upon the circuit between cathode and discharge controlling member, and means associated with the circuit between cathode and third electrode for producing an audible indication of the modulated high frequency current flowing therein, the circuit between cathode and third electrode being resonant 45 to the signaling frequency.
- 10 8. The combination in a signal receiving system of an electron discharge device having an electron emitting cathode, an anode, a third electrode and a discharge controlling member, electric circuits connecting said cathode with each of the other electrodes, sources of potential applied to said circuits in such a way as to produce a negative resistance in the circuit between cathode and third electrode, means for impressing signaling currents of radio frequency upon the circuit between cathode and discharge controlling member, means for modulating the signaling current at an audio frequency, and a detector circuit loosely coupled to the circuit between cathode and third electrode, the circuit between cathode and third electrode and the detector circuit being resonant to the signaling frequency, and the resistance of the circuit between cathode and third electrode being of a value greater than the critical value at which oscillations will be generated in the circuit. 50
- 15 9. The combination in a signal receiving system of an electron discharge device having an electron emitting cathode, an anode, a third electrode and a discharge controlling member, electric circuits connecting said cathode with each of the other electrodes, sources of potential applied to said circuits in such a way as to produce a negative resistance in the circuit between cathode and third electrode, means for impressing signaling currents of radio frequency upon the circuit between cathode and discharge controlling member, means for modulating the signaling current at an audio frequency, and means 55 associated with the circuit between cathode and third electrode for producing an audible indication of the modulated high frequency current flowing therein, the circuit between cathode and third electrode being resonant to the signaling frequency.
- 20 10. The combination in a signal receiving system of an electron discharge device having an electron emitting cathode, an anode, a third electrode and a discharge controlling member, electric circuits connecting said cathode with each of the other electrodes, sources of potential applied to said 60 circuits in such a way as to produce a negative resistance in the circuit between cathode and third electrode, means for impressing signaling currents of radio frequency upon the circuit between cathode and discharge controlling member, means for modulating the signaling current at an audio frequency, and means 65 associated with the circuit between cathode and third electrode for producing an audible indication of the modulated high frequency current flowing therein, the circuit between cathode and third electrode being resonant to the signaling frequency.
- 25 11. The combination in a signal receiving system of an electron discharge device having an electron emitting cathode, an anode, a third electrode and a discharge controlling member, electric circuits connecting said cathode with each of the other electrodes, sources of potential applied to said 70 circuits in such a way as to produce a negative resistance in the circuit between cathode and third electrode, means for impressing signaling currents of radio frequency upon the circuit between cathode and discharge controlling member, means for modulating the signaling current at an audio frequency, and means 75 associated with the circuit between cathode and third electrode for producing an audible indication of the modulated high frequency current flowing therein, the circuit between cathode and third electrode being resonant to the signaling frequency.
- 30 12. The combination in a signal receiving system of an electron discharge device having an electron emitting cathode, an anode, a third electrode and a discharge controlling member, electric circuits connecting said cathode with each of the other electrodes, sources of potential applied to said 80 circuits in such a way as to produce a negative resistance in the circuit between cathode and third electrode, means for impressing signaling currents of radio frequency upon the circuit between cathode and discharge controlling member, means for modulating the signaling current at an audio frequency, and means 85 associated with the circuit between cathode and third electrode for producing an audible indication of the modulated high frequency current flowing therein, the circuit between cathode and third electrode being resonant to the signaling frequency.
- 35 13. The combination in a signal receiving system of an electron discharge device having an electron emitting cathode, an anode, a third electrode and a discharge controlling member, electric circuits connecting said cathode with each of the other electrodes, sources of potential applied to said 90 circuits in such a way as to produce a negative resistance in the circuit between cathode and third electrode, means for impressing signaling currents of radio frequency upon the circuit between cathode and discharge controlling member, means for modulating the signaling current at an audio frequency, and means 95 associated with the circuit between cathode and third electrode for producing an audible indication of the modulated high frequency current flowing therein, the circuit between cathode and third electrode being resonant to the signaling frequency.

In witness whereof, I have hereunto set my hand this 22nd day of March, 1921.

BURKE BRADBURY.
